UNITED STATES PATENT OFFICE.

CHARLES P. WATSON, OF PHILADELPHIA, PENNSYLVANIA, ASSIGNOR TO WATSON ARMS COMPANY, INC., OF PHILADELPHIA, PENNSYLVANIA, A CORPORATION OF DELAWARE.

DETONATING-FUSE.

1,311,732.

Specification of Letters Patent. Patented July 29, 1919.

Application filed September 23, 1916. Serial No. 121,815.

To all whom it may concern:

Be it known that I, CHARLES P. WATSON, a citizen of the United States, residing at Philadelphia, in the county of Philadelphia and State of Pennsylvania, have invented 5 certain new and useful Improvements in Detonating-Fuses, of which the following is a specification.

My invention relates to percussion fuses 10 for ordnance shells and consists of the improvements illustrated in the drawings and which I will describe, by which the fuse is rendered safe under ordinary conditions of handling, positive in its operations when the 15 shell carrying it is fired from a gun, and which fuse is exceedingly simple in construction and consists of but few parts.

In the accompanying drawings I show the 20 preferred embodiment of my invention.

Figure 1 is a longitudinal sectional view 25 of the fuse, the parts being in unarmed or safety positions.

Fig. 2 is a similar view to Fig. 1, representing the fuse armed.

Fig. 3 is a transverse sectional view on the 25 line III—III of Fig. 1.

Referring to the drawings, 2 indicates the body of the fuse, which is preferably a steel plug adapted to be screwed into the breech 30 of a shell. It is centrally bored so as to form a relatively large powder chamber 3 at its inner end, and a communicating chamber 4 of smaller diameter toward the rear, in which is located a plunger 10 carrying the 35 firing pin 5. A partition 6 separates the chambers 3 and 4, being united to the plug 2 by screw threads. The partition is perforated at 8, and a percussion cap 7 is mounted at the outer end of this passage. In order 40 to cause a quick ignition of the powder charge within the chamber 3 I prefer to make the passage 8 of conical shape, its smaller end being toward the chamber 3, and to the cap being seated in the larger end, and to 45 fill the passage with a charge 9 of fine black powder. This powder charge upon being ignited causes a pencil of flame to be projected into the powder mass in the chamber

3 into which it bores for a considerable distance, forming a relatively large area of ignition that is carried well into the center of the mass. I have found that by contracting the passage 8 toward the chamber 3 the pencil of flame produced by the burning of the powder charge in the passage is projected 50 with unusual force and intensity, and with the result that the priming charge in the chamber 3 is more quickly ignited than when the bore through the partition is cylindrical. The firing pin is longitudinally movable to a limited extent within the plunger. It is formed with a head 11, and its stem occupies a longitudinal aperture in the plunger located opposite the cap 7. When the firing pin is retracted or drawn back into 55 the plunger, which is its safety position indicated in Fig. 1, the end of the firing pin is inside the face of the plunger and hence cannot come into engagement with the cap; while when it is moved forward into the armed 60 position indicated in Fig. 2, it projects a proper distance beyond the inner face of the plunger to effectively engage with the cap 65 when the plunger moves forward. In order to automatically control the movements of 70 the firing pin I mount, within a transverse recess 13 formed in the plunger, a cam 14 that is supported upon a pivot 15 on which it is free to oscillate. The cam is of irregular shape and formed with a shoulder 16, a 75 seat or depression 17, against which the head of the firing pin rests when the fuse is in unarmed position, and with a finger 18 that is adapted to lie in front of the head of the firing pin and between it and the end of the plunger, thus positively holding the pin in safety position when the cam occupies its 80 normal position represented in Fig. 1. The cam is held in this latter position by a locking bolt 19 that is adapted to lie partly in a shallow recess 20 formed in the inner end of the plunger and in a deeper recess 21 in the cam piece 15. A spring 22 located in the recess 21 behind the locking bolt 19 holds the latter forward. A pin 24, carried by the 85 cam piece 14, is arranged to move in a groove 90

95

or channel formed in the fuse body when the cam is moved from the position shown in Fig. 1 to that represented in Fig. 2, and to abut against a shoulder 25 when the parts 5 come to the position shown in Fig. 2, thereby arresting further movement of the cam and thus serving to maintain the parts of the fuse in proper armed position.

The cam is of eccentric shape, and the 10 position of its mass is such that it tends to move on its pivot 15 from the position indicated in Fig. 1 to that represented in Fig. 2 under the influence of centrifugal force due to the rotation of the shell in flight.

15 The operation of the fuse may now be set forth. When the parts occupy the positions indicated in Fig. 1 the fuse is unarmed and is safe to handle. The cam piece, by its finger 18, positively holds the firing 20 pin retracted, and the locking bolt positively holds the cam piece in the position indicated in Fig. 1; and this piece can only become unlocked by the conjoint operation of forces that act only when the shell carrying the 25 fuse is fired from a gun. When such firing takes place the plunger sets back violently within the chamber 4 and the locking bolt 19 sets back, compressing the spring 22 and freeing the plunger. The firing pin also 30 tends to set back, but is held in position by the engagement of its head with the seat 17 of the cam piece. The disposition of the mass of the cam piece is such, the greater amount being to the left of the axis of the pivot 35 15 when the parts are as they appear in Fig. 1, that the setting back tendency, due to the acceleration in the speed of the shell, causes the cam piece to positively maintain the position shown in Fig. 1, thus locking the firing 40 pin in safety position. Centrifugal force due to the rotation of the shell caused by the rifling of the gun now acts upon the cam piece and causes it, after passing the line of balance in front of the muzzle of the 45 gun where centrifugal force and set back due to acceleration are equal or just balance each other, to turn upon its pivot to the position indicated in Fig. 2. The turning of the cam piece first releases the firing pin 50 by withdrawing the finger from in front of its head, and then positively forces the pin into armed position by the engagement of the shoulder 16 with the head of the pin. The cam piece finally comes to rest with 55 the high point of the shoulder back of the firing pin, and this part of the cam may be formed into a flat face 23 to constitute a firm seat against which the pin rests when armed. Upon the shell striking the plunger 60 sets forward and carries the pin into engagement with the cap 7 which is thereby fired.

What I claim is:—

1. The combination, in a percussion fuse,

of a body supporting a firing pin longitudinally movable relative to the said body, and pivotally supported means movable when acted upon by centrifugal force and arranged to act on the firing pin and cause it to be moved longitudinally into armed position when the said means move due to centrifugal force. 65

2. The combination, in a percussion fuse, of a body supporting a firing pin longitudinally movable relative to the said body, 75 means pivotally supported in the said body and movable when acted upon by centrifugal force, arranged to act on the firing pin and cause it to be moved longitudinally into armed position when the said means move 80 due to centrifugal force, and means for locking the said pivoted, centrifugally operated, means against movement upon its pivot arranged to be operated to free the said means when the shell carrying the fuse 85 is being accelerated in flight due to being fired from a gun.

3. The combination, in a percussion fuse, of a body supporting a firing pin longitudinally movable relative to the said body, pivotally supported means movable when acted upon by centrifugal force and arranged to cause the firing pin to be moved longitudinally into armed position when the said means move due to centrifugal force, and 90 means for locking the firing pin in safety position carried by the said pivotally supported means and arranged to free the firing pin when the shell carrying the fuse is fired from a gun. 95

4. The combination, in a percussion fuse, of a plunger, a firing pin mounted in the plunger and longitudinally movable relative thereto, and a cam pivotally supported in the plunger arranged to be moved on its pivot by centrifugal force when the shell carrying the fuse is in rotation, and to act on the firing pin and move it into armed position. 105

5. The combination, in a percussion fuse, 110 of a plunger, a firing pin mounted in the plunger and movable relative thereto, a cam pivotally supported in the plunger arranged to be moved on its pivot by centrifugal force when the shell carrying the fuse is in rotation, and to act on the firing pin and move it into armed position, and a locking bolt for holding the cam arranged to be set back and free the cam when the shell carrying the fuse is fired from a gun. 115

6. The combination, in a percussion fuse, of a plunger in which is formed a longitudinal perforation and a transverse slot communicating with the perforation, a firing pin located in the said perforation and longitudinally movable therein, a cam pivotally supported in the slot and formed with a seat against which the firing pin rests 125

when in safety position, a shoulder for acting on the firing pin and moving it into armed position, and a locking finger for holding the pin in safety position, the cam 5 being arranged when free to turn on its pivot under the action of centrifugal force and cause its shoulder to act on the firing

pin and move it into armed position, and a locking bolt for holding the cam in safety position arranged to be moved to free the 10 cam when the shell carrying the fuse is fired from a gun.

CHARLES P. WATSON.
